CORRECTIVE MEANS FOR THE HUMAN FOOT

Erwin S. Lederman, Birmingham, Ala.

Application November 17, 1943, Serial No. 510,597

6 Claims. (Cl. 36—71)

This invention relates to corrective means for the human foot, particularly to supports for the arches thereof, and has for an object the provision of a device of the character designated which shall be simple and easy of application and which shall be adapted to support a weak and/or abnormal arch in its normal, healthy position, thereby affording the maximum of comfort to the user.

A further object of my invention is to provide arch supporting means for the human foot which shall combine the maximum of comfort with maximum support of the bones comprising the transverse arch, while at the same time creating a minimum of pressure on the plantar arteries in the foot, thus effecting a minimum of interference with circulation.

A further object of my invention is to provide a cushioned support for the transverse arch of the human foot which shall be effective particularly to afford a firm support for the scaphoid, internal cuneiform and cuboid bones of the transverse arch.

A very important object of my invention is to provide a cushioned support for the transverse arch of the human foot which shall be adapted to hold this arch level which is its natural position and which shall be adjustable longitudinally and as to height to adapt it to the needs of the particular user.

A still further object of my invention is to provide an arch support which shall be effective to hold the foot level with a firm support under the cuboid bone of the transverse arch at the outer side and under the scaphoid and internal cuneiform bones at the inner sides and one which shall not pinch the arteries and thus interfere with the circulation in the foot.

A device embodying these and other features of my invention is illustrated in the accompanying drawings, forming a part of this application in which;

Fig. 1 is a plan view of an innersole for a shoe having my improved supporting means incorporated therein, parts being broken away;

Fig. 2 is a plan view of an innersole for a shoe having my improved sole superimposed thereon to illustrate the difference in outline;

Figs. 3 and 4 are detailed views of small pads incorporated in the support at the sides thereof;

Fig. 5 is a sectional view taken along the line V—V of Fig. 1;

Fig. 6 is a plan view showing the skeleton of the human foot in dotted lines with my improved arch support superimposed thereon to illustrate

the relation of the support to the arch and the particular portions of the arch supported thereby;

Fig. 7 is a side view of a shoe broken away to show the human foot therein and showing the skeleton in dotted lines with the line of the flesh and skin of the foot, and my improved arch support incorporated beneath the arch; and

Fig. 8 is a view similar to Fig. 7 showing the opposite side of the shoe.

Referring to the drawings, I show in Fig. 1 an innersole 10 which preferably is made of relatively soft material covered with a soft leather covering 11 stitched around the edges as shown at 12. Along the sides of the forward part of the inner sole I provide elongated, relatively thin soft pads 13 and 14 which are adapted to bear against the side of the great toe and the head of the first metatarsal bone as well as the side of the little toe and the head of the fifth metatarsal bone and serve to prevent callouses from forming on the sides of said toes and the foot at said bones. Incorporated in the innersole is my improved arch support 16. The arch support comprises 3 separate sections 17, 18 and 19, the sections 18 and 19, at the sides, being generally triangular in shape, and provided with hinge grooves along the borders of said sections. The support is in the form of a pad of relatively firm material such as leather or rubber, with the hinge grooves 21 and 22 cut into the material to afford extra flexibility along the lines of the grooves. As shown in Fig. 1, the grooves 21 and 22 are relatively wide with their inner sides skived to slope toward the forward portion 17. Also, the area in the forward section indicated by the line 20 is slightly hollowed out in order that the pad shall not pinch the plantar arteries in the sole of the foot and impede circulation. The forward edges of the section 17 are skived, as indicated, to reduce the height of the support under the metatarsal bones, but the outer sides of the sections 18 and 19 are left unskived to afford ample support to the lateral bones of the transverse arch.

Incorporated in the arch support 16 are two small additional pads 23 and 24, shown in detail in Figs. 3 and 4, which raise the sides of the arch support still higher than the inner portion and thus afford special firm support to the cuboid, the scaphoid, and the inner cuneiform bones of the transverse arch, and act to relieve pressure on the plantar arteries. In order to prevent lateral spreading of the transverse arch, I provide a relatively soft pad 26, which is hinged to the innersole 10 along the side of the arch support to provide lateral support to the scaphoid and

inner cuneiform bones. Also, there is preferably incorporated in the inner sole 10 a heel support pad 27 which raises the outer side of the heel and is usually necessary in order to level up the heel bone and cause it to assume its normal vertical position. In weakened feet there is a tendency for the heel bone to roll over to the outer side.

On the under side of the innersole 10 is a pin 28, indicated in dotted lines in Fig. 1, for securing the innersole against forward displacement in a shoe.

In order that the shape of my improved innersole, as compared with the usual innersole of a shoe, may be seen, I show it in Fig. 2 with the usual innersole 29 superimposed thereon in dotted lines wherever it departs from the outline of my innersole. It will be seen that the parts 13, 14, 25 and 26 extend outwardly from the usual innersole 29 along the outer sides of the foot. The reason for the projections 25 and 26 is to afford a firm grip for the inner and outer sides of the transverse arch. It will also be seen that my improved support may be made narrower than the usual innersole in the area indicated by the numeral 30, the better to conform to the natural contour of the foot, which is narrower to the rear of the transverse arch than forward thereof.

In Figs. 6, 7 and 8, I show the relation of my improved arch support to the skeleton of the human foot. By referring to Fig. 6, it will be seen that the section 17 provides support for the middle cuneiform and external cuneiform bones of the transverse arch and for the rearward ends of the second, third and fourth metatarsals, and partial support for the bases of the first and fifth metatarsals. Section 19 is so shaped as to afford support to the internal cuneiform and scaphoid bones, while the section 18 is so shaped as to afford support to the cuboid bone of the transverse arch. The grooves 21 and 22 in the support permit hinge movements between the sections and further aid in providing a firm grip on the transverse arch. By referring to Figs. 7 and 8 the support afforded to the inner and outer bones of the transverse arch by the sections 18 and 19 will be further appreciated.

From the foregoing it will be seen that I have provided an improved arch support which is adapted to form an integral part of a shoe and can be removed and adjusted to accommodate the height of the transverse arch of the individual user and which fits under and affords support to the separate bones of the transverse arch. It will be further seen that my improved arch support affords a special support to the side bones of the transverse arch, leaving the inner portion of the support relieved so as not to impede circulation, and holding the arch in a raised, level position. It will still further be apparent from the foregoing description that by reason of the particular forms of the sections of the support and by reason of the means provided for the adjustment of the position of the supplemental support, I have provided for the maximum of comfort and utility to the user.

While I have shown my invention in but one form, it will be obvious to those skilled in the art that it is not so limited, but is susceptible of various other changes and modifications, without

departing from the spirit thereof, and I desire, therefore, that only such limitations shall be placed thereupon as are specifically set forth in the appended claims.

5. What I claim is:

1. A support for the transverse arch of the human foot comprising a sectional pad with the sections hinged together by weakening lines and including two sections extending forwardly from the heel line at the sides for affording firm transversely level support to the cuboid, the scaphoid and the inner cuneiform bones of the arch, and a third section extending forwardly of the other two sections for supporting the rearward ends of all the metatarsal bones.

10 2. A support for the transverse arch of the human foot comprising a sectional pad with the sections hinged together by weakening lines and including two sections extending forwardly from the heel line at the sides for affording firm transversely level support to the cuboid, the scaphoid and the inner cuneiform bones of the arch, a third section extending forwardly of the other two sections for supporting the rearward ends of all the metatarsal bones, and a section bent upwardly alongside the scaphoid and inner cuneiform bones of the transverse arch to afford lateral support thereto.

15 3. A support for the transverse arch of the human foot comprising a sectional pad with the sections hinged together by weakening lines and including two sections extending forwardly from the heel line at the sides for affording firm transversely level support to the cuboid, the scaphoid and the inner cuneiform bones of the arch, a third section extending forwardly of the other two sections for supporting the rearward ends of all the metatarsal bones, a section bent upwardly alongside the scaphoid and inner cuneiform bones of the transverse arch to afford lateral support thereto and relatively narrow supplementary pads disposed beneath the two sections at the sides to raise the sides of the arch higher than the central portion and relieve pressure on the plantar arteries of the foot.

20 4. A support as defined in claim 2 in which the said third section extends forwardly beneath the rearward ends of the metatarsal bones and terminates in a thin edge forwardly of said rearward ends.

25 5. A support as defined in claim 2 in which the sections at the sides are generally triangular in shape, the pad being provided with hinge grooves along the inner borders of said sections, and the central area of said pad is slightly hollowed out in order to free circulation in the plantar arteries.

30 6. A support for the transverse arch of the human foot comprising a pad having raised side portions extending forwardly from the heel line for affording transversely level support for the cuboid, scaphoid and inner cuneiform bones of the arch, and a third raised pointed portion extending forwardly beneath the rearward ends of the metatarsal bones, the area between said supporting portions being slightly hollowed out to free circulation in the plantar arteries.

ERWIN S. LEDERMAN.
